UNITED STATES PATENT OFFICE.

JAMES BARDSLEY, OF AKRON, OHIO.

DEVULCANIZING APPARATUS.

1,039,010.

Specification of Letters Patent. Patented Sept. 17, 1912.

Application filed December 31, 1910. Serial No. 600,227.

To all whom it may concern:

Be it known that I, JAMES BARDSLEY, a citizen of the United States, residing at Akron, in the county of Summit and State 5 of Ohio, have invented new and useful Improvements in Devulcanizing Apparatus, of which the following is a specification.

This invention relates to an apparatus for devulcanizing ground rubber waste or other 10 articles composed of ingredients having rubber as the principal part thereof, the object of the invention being to provide a simple, cheap and efficient apparatus of this class whereby all of the waste rubber is reclaimed, 15 so that it may again be used for any desired purpose.

With the above and other objects in view which will appear as the description progresses, the invention resides in the novel 20 construction, arrangement and combination of parts hereinafter fully described and claimed.

In the drawings, Figure 1 is a side elevation of a device constructed in accordance with the present invention. Fig. 2 25 is a central longitudinal section of the same. Fig. 3 is a transverse sectional view taken upon the line 3—3 of Fig. 2. Fig. 4 is a similar sectional view taken upon the line 30 4—4 of Fig. 2.

In the accompanying drawings, the numeral 1 designates a receptacle which is adapted to receive the ground rubber waste and chemicals. This receptacle is preferably 35 circular in cross section and has its inner faces lined with lead 2, or an analogous material which is not susceptible to the corrosive activities of the chemicals within the receptacle.

The receptacle 1 is centrally provided with two or more manhole openings having surrounding collars 3, and whereby the rubber scraps to be treated as well as the chemicals may be inserted within the receptacle. 40 The collars 3 are tightly closed through the medium of removable caps 4, the said caps as well as the collars being provided with a coating of non-corrosive material and the joint between the collars and caps being of 45 such an arrangement as to hermetically seal the openings of the receptacle.

The receptacle 1 has its inner portion provided with a plurality of spaced baffling plates, 5, the same being positioned longitudinally of the said receptacle and having their offset or radiating portions formed

with teeth 6 at the edges thereof. The teeth 6 of one of the baffling plates may be positioned to aline with the space between the teeth of the succeeding and preceding baffling plates, if desired, so that the rubber being treated within the receptacle will be positively contacted by the teeth and the said rubber thus rendered more easily soluble and the composition formed with the 60 rubber separated.

The collars provided upon the openings forming the manhole are so arranged in relation to the receptacle that the said receptacle will be counterbalanced thereby, 70 and the collars 3 and caps 4 thus materially assisting in the rotation of the receptacle in a manner which will presently be set forth.

The receptacle 1 is provided at suitable 75 spaced intervals with relief valves 7. These valves 7 are positioned a suitable distance adjacent the openings provided by the manholes and the said valves are protected through the medium of suitable reticulated 80 coverings designated by the numeral 8. The said coverings are preferably of a rectangular formation having an open bottom, the sides and ends of each of the said coverings being reticulated as heretofore set forth and each of the said covers being constructed of some suitable material not susceptible to the disintegrating effects of the chemicals within the receptacle. The receptacle is adapted for rotation and is centrally provided upon its opposite ends with enlarged pipe members 9. Each of the said pipe members is mounted in a suitable bearing 10, the said bearing being preferably provided with anti-frictional balls secured 90 upon the pipes or hollow shafts 9, the said pulleys being connected through the medium of suitable belting with a source of power and whereby the receptacle 1 may be rotated. Each of the hollow shafts 9 have their free 100 ends provided with packing boxes 13 and 14. Positioned within the hollow shaft 9 having the packing box 13 is a pipe member 15, the latter being provided with a suitable valve 16, the purpose of which will be presently apparent.

The hollow shaft 9 provided with the packing box 14 is provided with a pipe section 17. This pipe section is connected with a suitable injector 17 the latter communicating with a steam pipe 19 and being also connected with a water pipe 20. The in-

jector may be of any ordinary or preferred construction, and is provided with the usual operating handle whereby the steam is allowed within the said injector to pass therefrom through the pipe 17 and hollow shaft 9, to the receptacle 1. The water pipe 20 is provided with the usual valve 21 and the injector is also provided with an overflow pipe 22.

- 10 Extending longitudinally within the receptacle 1 is a perforated pipe 23. This pipe has one of its ends closed and its opposite end communicating with passages provided by the hollow shaft 9, pipe 17 and injector 18. The closed end of the pipe 23 is retained in position through the medium of a suitable support 24, while the outlet provided by the hollow shaft connected with the pipe 15 is protected through the medium 20 of a reticulated member 25.

Briefly stated, the operation of the device is as follows:—The ground rubber is inserted through one of the manholes of the receptacle 1, together with a sufficient 25 amount of chemicals which are adapted to assist in the process of reclaiming the rubber from the composition formed with the rubber. The valves are all closed. The cap is replaced upon the manhole and power is 30 applied through the medium of one of the pulleys to rotate the receptacle 1. The injector is then set so as to allow steam to pass through the pipe 19 and hollow shaft 9 into the perforated pipe 23. The steam is 35 ejected through the minute perforations of the pipe 23 in either direction, so that the radiating sprays contact the rubber particles and the chemicals. This process is kept up for a number of hours and when 40 sufficient time has lapsed to thoroughly soften the rubber to permit the particles comprising the composition to be removed therefrom, the steam from the injector is stopped and water is allowed to flow 45 through the pipe 20 to the reticulated pipe 23. The injector is then operated so that the steam from the pipe 19 will act upon the water from the pipe 20 so as to force the same rapidly through the perforations. 50 After mingling the water and steam with the chemicals within the receptacle for a sufficient length of time, the inflow of water and steam is cut off. The lowermost valves 55 are then opened and the water is permitted an outlet. After all the water has been removed from the receptacle one of the caps 4 is removed from the manhole opening and the reclaimed rubber withdrawn from the receptacle.

60 It is to be understood that the valve 16 connected with the pipe 15 is opened when

the steam and water are allowed to enter the receptacle 1, so that the base or composite material may find an outlet through this pipe 15. It is to be further understood that 65 when steam alone is being injected within the receptacle 1, the valve 16 is closed, so that the steam and chemicals are allowed a full and free action upon the rubber and composition.

Having thus fully described the invention, what I claim as new, is:—

1. A device of the class described comprising a cylindrical receptacle, a lining of non-corrosive material, diametrically opposite man-holes in said receptacle, removable closures for said man-holes, a plurality of diametrically opposite valved outlets for said receptacle, reticulated protectors for said valved outlets carried by the non-corrosive lining, hollow shafts carried by said receptacle, supports for rotatably mounting said shafts, means whereby said shafts may be operated, a reticulated protector carried by lining from one of the shaft openings, a pipe mounted within the other hollow shaft and extending into the receptacle, the inner portion of said pipe being perforated and having its end closed, and means by which fluid may be injected through said pipe into 90 the receptacle.

2. A device of the class described comprising a cylindrical receptacle having central openings in its ends, man-holes in said receptacle, closures for said man-holes, valved outlets in said receptacle, reticulated protectors for said valved outlets and one of the end openings carried by the receptacle, a plurality of baffle plates carried by the receptacle and arranged in longitudinal rows, teeth upon said baffle plates, the teeth on one plate being opposite the spaces between the teeth on the adjacent plates, hollow shafts carried by said receptacle and communicating with its end openings, means by which said shafts may be operated, supports for rotatably mounting said shafts, a fixed pipe mounted with one of said shafts and extending into the receptacle, the inner portion of said pipe being enlarged, perforated, and having its end closed, a fixed external support for said pipe, means for injecting fluid into the receptacle through said perforated pipe, and means whereby the flow of liquid may be 115 regulated.

In testimony whereof I affix my signature in presence of two witnesses.

JAMES BARDSELEY.
